UNITED STATES PATENT OFFICE.

JOSEPH DUKES THOMPSON AND WALTER THOMPSON, OF BIRMINGHAM, ENGLAND, ASSIGNORS TO WILLIAM WELLINGTON GREENER, OF SAME PLACE.

SINGLE-TRIGGER DOUBLE-BARREL GUN.

SPECIFICATION forming part of Letters Patent No. 610,569, dated September 13, 1898.

Application filed January 28, 1898. Serial No. 668,338. (No model.)

To all whom it may concern:

Be it known that we, JOSEPH DUKES THOMPSON, a resident of 36 Upper Highgate street, and WALTER THOMPSON, a resident of 86 Loddells street, in the city of Birmingham, England, subjects of the Queen of Great Britain, have invented new and useful Improvements in Double-Barrel Guns, (for which we have made application for patent in Great Britain, No. 15,544, bearing date June 30, 1897,) of which the following is a specification.

Our invention relates to improvements in double-barrel guns operated by one trigger; and our object is primarily to provide improved means whereby at choice either of the two barrels may be fired by the direct vertical action of the trigger upon the sear-levers or their substitutional equivalents, also to provide means whereby unintentional double firing is prevented. We attain these objects by the mechanism illustrated upon the accompanying drawings, in which—

Figure 1 is a side view showing this our invention when at rest. Fig. 2 shows the mechanism as when the right barrel is fired. Fig. 3 shows the changed position of mechanism as ready for firing the left barrel. Figs. 4 and 5 show detail side and plan views of the trigger. Figs. 6 and 7 show detail end and side views of the trigger-pull. Fig. 8 is a plan view showing the relative position of the two sear-levers. Figs. 9 and 10 are detached side and plan views showing the cam-stop device for preventing unintentional firing. Fig. 11 is a view further explanatory of the cam-stop device.

We have only shown those parts of a gun which are necessary to explain this our invention, and similar numbers refer to similar parts throughout the several views.

14 is the action-body, to which are secured in the ordinary manner the butt and also the barrels and upon which are carried the various firing mechanism.

15 is the trigger-plate, to which the trigger-blade 16 is pivoted, as usual, at 17. The rear part of this trigger-blade is gapped to receive the trigger-pull 18, which is pivoted at 19. The upper rear part of this pull is formed into an

arm 20, whose point 21 may be brought at will 50 into position beneath either of the sear-levers 22 23. In a state of rest the said arm is held beneath the lever 22 by means of the spring 24; but by a pulling pressure upon the pull 18 below the pivot 19, as indicated, for instance, by arrow 25, the point 21 is moved forward to the position beneath the lever 23.

22 is the sear-lever for firing the right-hand barrel, and 23 is the sear-lever for firing the left-hand barrel.

Now it will be seen that if the trigger be pulled in the direction of the arrow 26 the lever 22 is raised, as shown in Fig. 2, and the right-hand barrel is fired; but if instead of this the trigger is pulled in the direction of arrow 25 the point 21 is first thrown forward beneath the lever 23, and then the latter is raised, and thereby the left-hand barrel is fired, so that a choice may be readily made of which barrel shall be fired. Again, upon the upper side of the trigger-plate 15 is provided the cam-like piece 27, which acts in concert with the cam-like piece 28 upon the side of the arm 20 in such a manner that upon the upward movement of the trigger the point 21 75 shall be compelled to take a position beneath one or the other of the levers 22 or 23. (See Fig. 11.)

What we claim, and desire to secure by Letters Patent, is—

1. The combination in a lock of a gun having double barrels, of the trigger-pull 18, pivoted upon the depending pivoted trigger-blade 16, such trigger-pull having the arm 20 and point 21, to selectively raise either of the sears 85 of the lock, substantially as set forth and shown.

2. The combination of the movable cam-piece 28, upon the pivoted trigger-pull arm 20, with the fixed cam-piece 27, as set forth 90 and shown and for the purposes specified.

In witness whereof we have hereunto set our hands in the presence of two witnesses.

JOSEPH DUKES THOMPSON.

WALTER THOMPSON.
